UNITED STATES PATENT OFFICE.

EUGÈNE SCHNEIDER, OF LE CREUZOT, FRANCE, ASSIGNOR TO SCHNEIDER & CIE., OF PARIS, FRANCE, A LIMITED JOINT-STOCK COMPANY OF FRANCE.

EPISCOPE FOR TANKS AND OTHER USES.

1,311,294.

Specification of Letters Patent.

Patented July 29, 1919.

Application filed September 6, 1917. Serial No. 189,949.

To all whom it may concern:

Be it known that I, EUGÈNE SCHNEIDER, a citizen of the French Republic, and a resident of Le Creuzot, Saône-et-Loire, France, have invented a new and useful Improvement 5 in Episcopes for "Tanks" and other Uses, which invention is fully set forth in the following specification.

This invention has for its object to provide 10 an improved apparatus (hereinafter termed "episcope") to allow of the examination of a portion of the horizon by an observer sheltered in a "tank" or any other armored post, movable or fixed.

15 The improved apparatus is more particularly characterized by the mounting of the reflecting surfaces (mirrors or prisms) in a frame of thin metal which is fitted in a removable manner in an armored casing, the 20 front of which may be constituted by the armor of the actual shelter, while the other walls are formed by the sides and back of a casing fixed to the said armor. One of the 25 sides of this casing is open to allow of introducing and removing the frame carrying the mirrors or prisms. The said frame is normally held in its armored lodgment by a retaining device, such as a spring catch or fixing screws.

30 The invention is further characterized by the feature that one of the reflecting surfaces (the objective) is journaled in the frame of thin metal on a horizontal axle, so that the 35 said reflecting surface may be inclined at different angles by means of a suitable actuating device operated by the observer inside the shelter.

Several embodiments of this invention are 40 illustrated by way of example in the accompanying drawings in which:-

Figures 1, 2 and 3 illustrate a first embodiment; Fig. 1 being a vertical section on the line I—I of Fig. 2; Fig. 2 being a vertical section on the line II—II of Fig. 1, and Fig. 45 3 being a rear elevation.

Fig. 4 is a side elevation of a modification.

Figs. 5 and 6 show a further modification, Fig. 5 being a vertical section on the line V—V of Fig. 6, and Fig. 6 being a side elevation on the line VI—VI of Fig. 5.

In all these figures, A is the wall of the armored shelter to which the armored casing for the episcope is fixed. A portion of said wall forms the front or cover of the casing. 55 a is an aperture for the entrance of the light

rays, formed in the wall A opposite the back B of the casing. One of the sides of the casing, for instance the longitudinal side opposite to B³ (in the embodiment shown in Figs. 1 to 3), or the lower transverse wall 60 opposite to B¹ (in the embodiment shown in Figs. 5 and 6) is omitted for the purpose of enabling the rapid introduction and removal of the thin metal frame C in which are mounted the mirrors or prisms D, E. This 65 frame C when engaged in its armored lodgment, is held in place either by means of a spring catch F (Figs. 2 and 4) or by means of screws G (Figs. 5 and 6).

The mirror or reflecting prism E may be 70 fixed in the frame C, and will be situated, when the said frame is placed in its lodgment, opposite an aperture b formed in the back of the casing. This back is preferably 75 provided with hooks or ledges b¹, b² for the purpose of guiding and supporting a removable thick pane of glass H.

The mirror or prism D which receives the 80 light entering through the aperture a, is adapted to move on a longitudinal axle d journaled in the vertical sides of the frame C, in such a manner that the surface that receives the images may be inclined at any desired angle.

In the example shown in Figs. 1 to 3, the 85 various inclinations are produced by operating a knurled knob D¹ which rubs with a fluted surface d¹ against a flexible support d² formed on the boss D² in which the axle d is journaled.

In the modification shown in Fig. 4, the 90 rotation of the mirror D is effected by means of a lever I fixed on the axle d and provided at its free end with a head i engaging with a fluted arc I¹ fixed on the longitudinal side of the frame C.

In the examples shown in Figs. 5 and 6, J is a spring attached at one end to the upper transverse side of the frame C, and at its other end to the holder or supporting backing of the mirror D, in such a manner that the spring J has a constant tendency to pull up the mirror D. Any desired inclination may be given to the mirror by means of a screw K which bears with its end upon the 100 holder of the mirror and is adapted to be operated by means of a knurled knob K¹.

A broken mirror or prism can be rapidly 105 replaced by the complete replacing of the frame C and the parts carried by the latter.

For this purpose it is merely necessary to carry in the tank or other armored shelter, one or more similar spare frames.

That part of the back B of the casing which may be liable to be struck by bullets entering through the aperture a, may be reinforced by a plate L of extra hard metal which may be removable as shown in Figs. 1 and 3; the said plate L being kept fixed in its lodgment by means of a screw L'.

What I claim is:—

1. In an eposcope affixed to an armored shelter such as a "tank," for enabling an observer inside to gain a view of a portion of the horizon, the combination with the armored wall of the shelter, pierced with an inlet aperture for the entrance of the light from the outside, of an armored casing, fixed to the inside of said armored wall, formed with an exit aperture for light from said casing, and with a side opening, a removable frame made of thin metal adapted to be introduced through said side opening in said casing, a first reflector in said casing arranged to receive light entering through said inlet aperture, and a second reflector in said casing arranged to receive the light reflected from said first reflector and to reflect same through said outlet aperture to the eye of the observer inside the shelter.

2. In an eposcope affixed to an armored shelter such as a "tank," for enabling an observer inside to gain a view of a portion of the horizon, the combination with the armored wall of the shelter, pierced with an inlet aperture for the entrance of the light from the outside, of an armored casing, fixed to the inside of said armored wall, formed with an exit aperture for light from said casing, and with a side opening, a removable frame made of thin metal adapted to be introduced through said side opening in said casing, a first reflector in said casing arranged to receive light entering through said inlet aperture, and a second reflector in said casing arranged to receive the light reflected from said first reflector and to reflect same through said outlet aperture to the eye of the observer inside the shelter, and means operable from inside the shelter for vary-

ing the angular position of said first reflector.

3. In an eposcope affixed to an armored shelter such as a "tank," for enabling an observer inside to gain a view of a portion of the horizon, the combination with the armored wall of the shelter, pierced with an inlet aperture for the entrance of the light from the outside, of an armored casing, fixed to the inside of said armored wall, formed with an exit aperture for light from said casing, and with a side opening, a removable frame made of thin metal adapted to be introduced through said side opening in said casing, a first reflector in said casing arranged to receive light entering through said inlet aperture, and a second reflector in said casing arranged to receive the light reflected from said first reflector and to reflect same through said outlet aperture to the eye of the observer inside the shelter, the inside back surface of said casing being reinforced opposite said inlet aperture with a plate of extra hard metal.

4. In an eposcope affixed to an armored shelter such as a "tank," for enabling an observer inside to gain a view of a portion of the horizon, the combination with the armored wall of the shelter, pierced with an inlet aperture for the entrance of the light from the outside, of an armored casing, fixed to the inside of said armored wall, formed with an exit aperture for light from said casing, and with a side opening, a removable frame made of thin metal adapted to be introduced through said side opening in said casing, a first reflector in said casing arranged to receive light entering through said inlet aperture, and a second reflector in said casing arranged to receive the light reflected from said first reflector and to reflect same through said outlet aperture to the eye of the observer inside the shelter, the outside back surface of said casing being fitted with a removable protecting pane of reinforced glass opposite said outlet aperture.

In testimony whereof I have signed this specification.

EUGÈNE SCHNEIDER.
